UNITED STATES PATENT OFFICE.

SHELLEY GULICK, OF BARNES, LONDON, ENGLAND.

BUTTON.

1,397,957.

Specification of Letters Patent.

Patented Nov. 22, 1921.

Application filed May 3, 1920. Serial No. 378,636.

(GRANTED UNDER THE PROVISIONS OF THE ACT OF MARCH 3, 1921, 41 STAT. L., 1313.)

To all whom it may concern:

Be it known that I, SHELLEY GULICK, subject of the King of Great Britain, and residing at 107 Riverview Gardens, Barnes, 5 London, S. W., England, have invented certain new and useful Improvement in or Relating to Buttons, (for which I have filed application in England Feb. 5, 1915, Patent No. 1,860,) of which the following is a specification.

This invention relates to button blanks, for use on wearing apparel and upholstery, which are adapted to be covered with cloth or other material. When it is desired to 15 employ buttons covered with the same material, the present method is to cover an ordinary button or blank and fasten the material at the back thereof by sewing or binding with thread or the like. In order to 20 do this neatly difficulty is experienced and a certain amount of time is spent in the operation and in the majority of cases where a number of buttons have to be covered the work is given to some person who specializes 25 in such work.

The object of this invention is to obviate these disadvantages and to provide an improved button blank which can be rapidly covered with any material, and can be manufactured at small cost.

According to this invention the button blank consists of two plates which are adapted to be clamped together by means of a bifurcated member.

35 In the drawings:

Figure 1 is a front view of one of the parts of the button blank.

Fig. 2 is a plan view of the other part or back plate of the button blank.

40 Fig. 3 is a perspective view of one form of bifurcated member.

Fig. 4 is a sectional view of the parts of the button blank before assembling them.

Fig. 5 is a perspective view of the parts 45 of the button with the front covered, ready for clamping together.

Fig. 6 is a back view of the complete covered button.

Fig. 7 is a sectional view of the complete 50 covered button.

The two plates consist of a main plate *a* which is adapted to be covered with material *g*, and a back plate *b* or washer smaller in diameter and provided with a shank or 55 eye *c* or any other means for attachment to

the garment or the like. The bifurcated member *d* preferably consists of a substantially U-shaped strip of pliable metal which is adapted to be inserted through two slots *e*, *e*, from the face of the main plate *a* and 60 passing through two corresponding slots *f*, *f*, in the back plate *b*.

The main plate is preferably made convex with its periphery slightly lipped as at *h* and the back plate is made concave with the 65 periphery dished at *i*, in order to grip the material when clamped.

Portions of the main and back plates are preferably countersunk as at *j* and *k* respectively in order that the base and prongs of 70 the bifurcated member *d* may lie flush when the prongs are bent back.

If desired one or more washers may be provided between the main plate and back-plate.

The plates may be made of any suitable 75 material and may be of any desired shape or size.

The back plate *b* may be provided with a central hole instead of the shank or eye *c* 80 in order that a portion of the material may be passed through and sewn to the garment or the like.

In order to clamp the said two plates together the prongs of the bifurcated member 85 *d* are bent back upon the back plate *b* as shown in Fig. 3 clamping the material *g* therebetween.

A button blank made in accordance with this invention may be very easily covered 90 with the desired material by any person with the greatest facility, while the blank can be manufactured at small cost.

I claim:—

1. A button blank comprising two plates 95 with means for clamping the two plates together after one part has been covered by material.

2. A button blank comprising two plates with manually operable means for clamping 100 the two plates together after one has been covered by material.

3. A button blank comprising two plates, a front plate and a back plate, each having slots therein, and a bifurcated clamping 105 member the legs of which may be passed through the slots after the button front plate is covered with material, and bent over so as to clamp the plates together.

4. A button blank comprising two plates, 110

- a front plate and a back plate, slots in each plate, a depression in the central portions between the slots of the front plate, and depressions adjoining the outer side of each 5 slot of the back plate, with a clamping member of bifurcated form for engaging the slots of said plates, said member having a central bridge part to seat in said central depression of the front plate.
- 10 5. A button blank comprising two plates, a front plate and a back plate, means on the back plate for attaching said blank to an article, and a bifurcated member for clamping said plates together.
- 15 6. A covered button comprising front and back plates a covering of material for the

front plate, means on the back plate for attaching the button to an article, a separable bifurcated member for clamping said plates together to retain the covering on the front 20 plate.

7. A covered button comprising front and back plates a covering of material for the front plate, means on the back plate for attaching the button to an article a separable 25 bifurcated member for clamping said plates together to retain the covering on the front plate said member being engaged with the front plate before said covering is attached.

In testimony whereof I affix my signature. 30

SHELLEY GULICK.
